ATTORNEY.

UNITED STATES PATENT OFFICE.

AZARIAH HORACE HASTINGS, OF NEW YORK, N. Y.

PIANO-ACTION.

SPECIFICATION forming part of Letters Patent No. 450,572, dated April 14, 1891.

Application filed July 25, 1890. Serial No. 359,863. (No model.)

To all whom it may concern:

Be it known that I, AZARIAH HORACE HASTINGS, a citizen of the United States, and a resident of New York city, in the county of 5 New York and State of New York, have invented certain new and useful Improvements in Piano-Actions, of which the following is a specification.

My invention relates to improvements in up-right-piano actions, and has for its object the production of an action of peculiarly rapid-repeating properties which shall be easy of adjustment and nice regulation, simple in construction, and not liable to get out of order.

15 To this end my invention consists in the novel arrangement of the hammer-butt and hammer-check, jack-escapement, repeating and hammer springs, all as hereinafter more specifically described, and pointed out in the 20 claims.

In the accompanying drawings, illustrating my invention, in which like parts are designated by similar letters of reference, Figure 1 is a side elevation, partly in section; and Fig. 25 2 is a detached view of the repeating-spring.

B is the usual jack, working on the hammer-butt A to throw the hammer forward and strike a string and has its lower end pivotally connected to the jack-lever C, and is provided 30 with the spiral spring a for maintaining the jack in the position shown. The escapement for the jack B consists in a light flexible piece D, attached to said jack or formed integral therewith, having its upper end cushioned to 35 prevent noise when it strikes the shoulder b on the hammer-butt, and adjusted in the most effective position by the regulating-screw c, passing through the jack B and bearing upon the cushion of the piece D, before described.

40 Immediately above and curving over the top of the jack B is the repeating-spring E, which is rigidly secured to hammer-butt A in any suitable manner, but preferably by confining it in a recess in said hammer-butt. This

45 spring may be of the form illustrated in Fig. 2, and is cushioned, as shown, and provided at its outer extremity with a cushion or stop to check the outward motion of the jack B.

When the jack B is operated to throw the 50 hammer forward and strike a string, it is obvious that it will act against the tension of

repeating-spring E, which the instant the performer's finger leaves the key J throws the jack to its normal position, aided by the spiral spring a, thus permitting the same string 55 to be again struck without raising the finger entirely from the key or waiting for the "full action" to take place, as in the present movements. To quicken the action of the hammer and hasten its return to its normal position, 60 I employ the wire hammer-spring F, secured at one end to the hammer-rest rail I or to a special rail under the same. This arrangement of the hammer-spring is peculiarly effective and advantageous, for said spring, 65 working on the hammer-butt at the side of the shank opposite to the face of the hammer, pulls said hammer into its normal position, and, being at the rear of the hammer, interposes no obstacle to the free access to the 70 flanges and does away with the ordinary rail and springs between the hammer shank and dampers, and having its other end free to work in the recess d of the hammer-butt A. The hammer-butt A is provided with the downwardly-extending bumper G for checking the fall of the hammer, which in operation is engaged by the check H, secured at one end to the jack-lever C by the spring or pivot center e as near the lever center of C as possible and 75 having its outer end free to be adjusted by the regulating-screw f.

It will be noted that by my combination of devices the highest efficiency is obtained with the least complication of parts and a minimum of friction, by the position of the stops lost motion is avoided, and by the arrangement of the springs the action is rendered unusually rapid.

It will of course be understood that the parts 90 illustrated in the drawings and not herein specifically described may be of ordinary construction and arrangement.

What I claim as my invention, and desire to secure by Letters Patent, is—

1. The hammer-butt A and jack B, in combination with the repeating-spring E, having its center of movement in said hammer-butt, substantially as specified.
2. The hammer-butt A and jack B, the latter pivotally connected to the jack-lever C, in combination with a spring for maintaining

said jack in its normal position and a repeating-spring having its center of movement in the hammer-butt, substantially as specified.

3. The hammer-butt A and jack B, in combination with a spring for accelerating the return of the hammer to its normal position, secured at one end to the hammer-rest rail and having the other end free to operate in a recess in the hammer-butt at the side opposite to the face of the hammer, substantially as specified.

4. The hammer-butt A and jack B, in combination with a spring for accelerating the return of the hammer to its normal position, secured at one end to a special rail for the purpose beneath the hammer-rest rail and having its other end free to operate in a recess in the hammer-butt at the side opposite the face of the hammer, substantially as specified.

5. The combination, with the hammer-butt A and jack B, of the downwardly-projecting bumper G and spring-check H, pivotally connected to the jack-lever C near the lever center thereof, and means for regulating the po-

sition thereof, substantially as shown and described.

6. In an upright-piano action, a hammer-butt having a downwardly-projecting bumper and a spring-stop for checking the movement of said hammer-butt, in combination with a jack for raising said hammer-butt, a light strip working with the jack for aiding its escapement, and a repeating-spring, all arranged to operate substantially as described, for the purposes set forth.

7. The combination of the hammer-butt A and jack B with the escapement device D, consisting of a flexible strip having its lower end fast to said jack and having its upper end cushioned and free to be adjusted, and means for adjusting the same, substantially as specified.

Signed at New York city, in the county of New York and State of New York, this 2d day of June, A. D. 1890.

AZARIAH HORACE HASTINGS.
